UNITED STATES PATENT OFFICE.

ARTHUR W. RIVETT, OF CHICAGO, ILLINOIS, ASSIGNOR TO J. J. RYAN & CO.,
OF SAME PLACE.

DESIGN FOR A CHAIN-GUARD FOR BICYCLES.

SPECIFICATION forming part of Design No. 27,832, dated November 9, 1897.

Application filed April 22, 1897. Serial No. 633,409. Term of patent 3½ years.

To all whom it may concern:

Be it known that I, ARTHUR W. RIVETT, of Chicago, in the county of Cook and State of Illinois, have invented and produced a new 5 and original Design for Chain and Sprocket-Wheel Guards for Bicycles, of which the following is a specification.

Referring to the appended drawings, Figure 1 illustrates a chain and sprocket-wheel 10 guard embodying my design as seen in side elevation. Fig. 2 is a transverse vertical sectional view taken on line 2-2 of Fig. 1 and looking toward the front end of the guard.

The essential features of my present design 15 embrace an outer skeleton frame or rim A, of generally ovoid form, made externally smooth and continuous except for a single opening or interruption at the rear end of the guard, hereinafter more particularly described, and provided around its entire inner margin with a 20 series of scallops, a ring arranged concentrically within the larger end of said outer rim, made of a series of scallops, and a longitudinally-arranged slot or opening extending from 25 the rear end of the guard forwardly along the median line thereof throughout approximately one-half the length of the latter, this slot or opening being outlined by bars, each of which is also made up of a series of 30 connected scallops. The space surrounding said longitudinal opening and that surrounding the circular opening formed by the ring at the front end of the guard may be variously filled in without substantially changing 35 the general appearance of the design—as, for instance, by the scrollwork herein shown.

Describing the guard in detail, the front end a, which is the larger end of the guard, is made in the form of a true circle, (to conform to the front driving-sprocket of the bicycle,) and straight upper and lower side margins a' extend tangentially therefrom rearwardly and convergently, so as to extend approximately parallel with the drive-chain of the bicycle. The guard terminates at its rear in a gracefully-rounded end a². The inner margin of the rim is provided with a series of uniformly-shaped scallops, being arranged contiguous to each other, so as to meet at their ends and form intervening points a⁴. The upper side member of the

rim is provided with an instanding flange a⁵, which is also extended entirely around the circular forward end of the guard, but is omitted from the lower side thereof, as indicated clearly in the drawings.

At the front or larger end of the guard a circular opening a⁶ is provided arranged concentrically with the circular end of the guard and bounded or outlined by a ring A', 60 which is composed of a series of scallops a⁷ of uniform width, but curved reversely from the scallops of the outer rim, the several scallops of the ring and rim being arranged exactly opposite and directed toward each other. The distance between the inner ring and the outer frame is such that the points of the scallops do not quite meet, and throughout the front half of the circumference of the ring the space intervening between the points 70 of the scallops is bridged by means of ball-shaped ornaments a⁸, which serve to unite the ring with the outer frame.

From the rear end of the guard an opening a⁹ extends forwardly along the median line 75 thereof to a point approximately midway of the length of the guard, said opening being bounded by two bars a¹⁰, arranged to extend generally parallel to each other and each composed of a continuous series of scallops 80 uniform in appearance with the scallops of the outer rim. Between the forward end of the longitudinal opening a⁹ and the proximate side of the ring is arranged a rosette-shaped scroll a¹¹, the size of this scroll being 85 such as to completely occupy the space intervening between the end of the opening a⁹ and the ring. In the somewhat triangular-shaped spaces between the rosette the ring and the outer rim are arranged suitable scrolls a¹², 90 and the spaces extending rearwardly from the rosette, between the outer rim and the parallel bars a¹⁰, are occupied by series of scrolls a¹³ of gradually-decreasing size to correspond to the rearwardly-tapering form of 95 the guard. When in position upon the bicycle, the interruption in the outer rim formed by the longitudinal opening a⁹ will be occupied by the rear lower fork member of the wheel, and the guard will therefore 100 present in appearance a continuous outline. The guard constructed as described serves

to effectually protect the garments of the rider from the front sprocket and drive-chain, it being understood that the guard shown herein is not intended to extend over 5 the rear sprocket-wheel.

I claim—

The design for a chain and sprocket-wheel guard for bicycles substantially as herein shown and described.

In testimony that I claim the foregoing as to my invention I affix my signature, in presence of two subscribing witnesses, this 20th day of April, A. D. 1897.

ARTHUR W. RIVETT.
